RADIATION CURRENT SOURCE

Harald H. Rossi, Orangeburg, N. Y., assignor to the United States of America as represented by the United States Atomic Energy Commission

Application June 6, 1950, Serial No. 166,489

2 Claims. (Cl. 315—150)

1

The present invention relates to a variable source of minute currents. In the measurement of extremely small currents in the order of 10^{-12} amperes a secondary source of very small current is often required. Accurate measurements of such currents can be made, for example, with a sensitive electrometer by balancing a known current against an unknown current so that the electrometer does not deflect. It is also sometimes desirable to have a source of current the absolute value of which is not known but which remains constant or which may be varied reproducibly. The present invention provides a source of current which remains constant or which may be varied reproducibly over extended periods of time. By calibrating the source such as is provided according to the present invention with sources of known intensity a source of known current intensity may be produced.

It is accordingly an object of the present invention to provide a variable source of minute currents which may be varied reproducibly.

It is another object of the present invention to provide an apparatus which can supply minute currents over a relatively wide range.

It is a further object of the present invention to provide a method of producing minute currents with high accuracy and reproducibility.

Other objects and advantages of the present invention will be in part obvious and in part pointed out hereinafter.

In one of its broader aspects the objects of the present invention may be achieved by providing an apparatus comprising a container for enclosing a gas at a known pressure, a source of charged particle radiation disposed in said container, a plurality of ion collector plates in said container, at least one of said plates being adapted to be moved relatively to an at least partially shielded ion collector plate, said ion collector plate being insulated from said movable plate and from said container, and an electrical conductor communicating between said collector plate and the container exterior through an insulated port.

The subject apparatus is described with reference to the accompanying drawing, wherein:

Figure 1 is a transverse sectional view of the current source of the present invention taken along line 1—1 of Figure 2, and

Figure 2 is a vertical section of the current source of Figure 1 taken on the line 2—2 of Figure 1.

It will be understood however that the embodiment disclosed herein is given primarily for illustrative purposes and is not intended to be understood as limiting the scope of the present invention. Therefore substantial variations and substitutions may be made in the elements of the disclosed invention without departing from the scope thereof.

5 In carrying out the method of the present invention in one of its broader aspects, gas in a container is ionized by emanations from a radioactive source, a potential is impressed on electrodes in the container to cause the ions to move, a collector electrode is interposed in the path of the moving ions, and a movable shield is disposed adjacent said collector electrode to collect at least a portion of the ions which move toward said collector electrode.

An apparatus for carrying out this method is described with reference to the drawings.

15 The apparatus of this particular embodiment comprises generally a radioactive source 12 within a container 10. The source is kept at a high potential and the container at ground potential. The radiation from the source 12 causes ionization of gas in the container 10. Due to the high potential between source 12 and container 10 ions are caused to move in generally radial directions within the container. In so moving they impinge on collector plates 16, 18 and 72 causing a charge to accumulate on the collector plates. If the charge is removed as fast as it is collected 20 a relatively constant current will flow from the collector plates.

25 The apparatus is described in greater detail with reference to the Figures 1 and 2. A container 10 encloses an ionization chamber. The container consists of a cylindrical tube 54 which forms the outer wall of the container and of a top plate 56 and a bottom plate 58 which form the top and bottom of the container. Within the container two insulator rings 22 and 24 are positioned at the bottom and top of the container respectively. These insulated rings support a plurality of ion collector plates 18 and 72. These collector plates are in the form of radial segments of tubes extending around an arc of about 120 degrees.

30 40 Plates 18 and 72 are positioned in generally concentric relation to the tube 54 and the source of charged particle radiation 12. The shield plate 16 is also in the form of a radial segment of a tube extending around an arc of about 120°.

45 50 It is disposed in the container on the concave side of plates 18 and 72 but is eccentric in its relation to the tube 54 and source 12. The outer longitudinal edge of the plate 16 is preferably bevelled to provide a blade edge at its outer surface.

55 The plate 16 is attached to and supported at its upper end by flange plate 66 and at its lower end by a similar plate 64. The flange plates 64 and 66 are rotatably supported in the chamber by their respective tubular extensions 67 and 65. Tube 65 extends through upper plate 56 and rests against its inner surface at shoulder 69. The end of tube 67 thrusts against the inner surface of bottom plate 58 and is held in position by an insulator 14 extending through the tube core. 60 The lower flange plate 64, the shield plate 16 and

the upper flange plate 66 may be rotated as a unit. The handle 20 is attached to the externally extending portion of tube 65 in order to provide means for rotating the shield plate 16 within the chamber. The handle 20 is held to the tube 65 by the set screw 21. Thus by rotation of the handle 20 the flange plates 64 and 66 are rotated and the shield plate 16 may be disposed at any desired position within the chamber. The bladed edge of shield plate 16 is brought close to the concave surface of collector plate 18 as the handle 20 is rotated. This arrangement is preferred in order to minimize the change in capacitance between the members 16 and 18 as the shield plate 16 is shifted. The change in capacitance is minimized with this arrangement because as is apparent from Figure 1 the bladed edge of the shield plate is relatively close to the collector plate 18 and thus carries most of the capacitance existing between the two plates. As the shield plate 16 is shifted in its position with relation to plate 18 the bladed edge remains in close proximity to the plate 18 and since it carries most of the capacitance little change in capacitance between the members results from shifting of the plates.

Ionization of the gas in container 10 is produced upon radiation from a radioactive source 12. This source emitting preferably beta radiation is positioned in a generally axial position with respect to the cylindrical chamber wall 54. A foil of silver containing approximately ten milligrams of radium may be used and the foil may be enclosed as a strip within an axially extending glass tube 12. The tube is preferably sealed at one end and imbedded at the other into a metal cup 50 by a sealing composition or wax 52. The exterior surface of the glass tube is preferably made conducting by coating with graphite or a similar conducting composition. It is desirable to employ an hermetically sealed container such as the glass tube 12 in order to prevent the radon gas, emitted from the radium source, from contaminating the chamber enclosed within the container 54. The electrically conducting external surface of the tube 12 is electrically connected to a source of potential through the metal cup 50 and rod 51. Rod 51 is insulated from the bottom plate 58 of the container 10 and from lower flange plate 64 by the insulator 14. The insulator sleeve 14 is threaded at its externally extending portion to receive the locknut 60. By tightening the nut 60 against the outer surface of the plate 58, a shoulder 59 on the insulator sleeve 14 is urged into contact with the inner surface of the plate 58. A second locknut 62 may be threaded onto the externally extending portion of the rod 51 to retain it in position in the insulator 14. By removal of the nuts 60 and 62, the tube 12 and rod 51 may be removed through the port 68 and replaced as desired by a source of greater or lesser intensity. The internal end of the insulator 14 is fitted axially into the hole in the lower flange plate 64 thereby providing an axis about which the plate may be rotated.

The operation of the current source is generally as follows. The high potential is applied to the conducting surface of the tube 12. The container 10 is connected to ground. This grounds the shield plate 16 which is electrically connected to the container 10. The collector plate 18 is not grounded but is insulated from the container 10 by the upper and lower insulators 24 and 22 respectively. The radioactive source emits beta particles in all directions generally radially from

the tube 12. Ionization of the gas within the container 10 provides a source of charged particles which can carry a charge between conducting surface of tube 12 and the container wall 54. The high voltage applied between the conducting surface of the rod 12 and the container wall 54 induces radial motion of the ions and thus causes a charge to collect on plate 18. Charge collected on plate 18 may be removed as a minute current through externally communicating conductor 26. The position of the shield plate 16 determines how many of the charged particles can impinge on the plate member 18 because the plate 16 can be located between the plate 18 and the source 12 where it intercepts ions accelerated toward plate 18. Thus, when a large number of positively charged particles are formed in the region ambient to the source 12 and a high potential is applied to the source tube 12 while the container 10 is grounded, positive ions will proceed generally radially from the source 12 toward the container wall 54. If the plate 16 is positioned to shield part of the surface of the plate 18 from the radially moving ions, a portion of the ions will impinge on the plate 16 and another portion will impinge on the plate 18. The number of ions impinging on plate 18 may be changed by changing the portion of plate 18 shielded by plate 16. It is possible to change the ion current in still a third way. If the position of the plate 16 and the intensity of the radiation from the source 12 are kept constant and the container 10 is hermetically sealed by plugging port 68, an ion current will flow to the plate member 18 which is roughly proportional to the pressure of the gas enclosed within the container 10.

It is possible to provide minute currents over a very wide intensity range by presetting three parameters. That is, the intensity of the ion current may be changed by changing (1) the intensity of the radiation source, (2) pressure of the gas in the container 10 and (3) the position of the plate 16 relative to the plate 18. By providing an hermetically sealed chamber within the container 10 and a source of known intensity, the sole variable is the position of the plate 16 with respect to the plate 18. The chamber may be sealed by closure of port 68. It is therefore possible to adjust the apparatus to a certain current range by selection of source intensity and adjustment of pressure, and then to vary the current entirely by rotating the handle 20. The handle position for various source currents may be calibrated so that by adjusting the position of the handle 20 a certain current will flow. This is true if the voltage developed on the collector 18 is small with respect to the voltage impressed between tube 12 and the container 10.

As previously stated the embodiment disclosed is illustrative of the present invention. The invention may be embodied in many alternate devices without departing from the scope thereof. For example, a rod of strontium metal or other high energy beta ray emitter having a long half life might be used. Such a rod might be prepared, for example, by inserting it into a nuclear reactor for a sufficient length of time to give it the desired activity. This type of rod source does not emit radon.

The configuration of the disclosed embodiment, wherein a movable plate is positioned eccentrically to the tubular arrangement of the apparatus, is used principally because there is a danger of a troublesome capacitance being developed between the two plate members 16 and 18. The

knifing of one edge of the plate 16 helps to minimize the effects of a capacitance development as explained above. The arrangement disclosed is satisfactory for producing a constant current over an extended period of time. However, changing of the current delivered by shifting the vane 16 may result in changing the capacitance between the plate members. A change in the capacitance results in the production of a pulse current or current "kick." It is possible to avoid this latter result by attaching a second chamber having exactly the dimensions of the first but containing a "source" 12' which is not radioactive. The second chamber is attached so that the shifting of its plates compensates for the change in capacitance between the plates of the first chamber. Such a chamber may be positioned, as indicated in phantom view at the top of Figure 2, as a mirror image of the apparatus described in the embodiment. In this compensating arrangement the movement of the calibrated handle 20-20' results in the rotation of a plate 16 in the radioactive portion of the apparatus and a plate 16' in the non-radioactive mirror image of the apparatus. External brackets 10' may be used to join the upper and lower chambers 10 and 10', to prevent their relative rotation when the handle 20 is rotated.

It is also possible to provide a greater range of available current intensities from such a source by inclusion of auxiliary plate members such as 72 having shorter lengths than plate 18 but disposed in the same circle as plate 18 within the container 10. The shield plate 16 may be used to partially shield the auxiliary plates or the collector plate 18 alternately. A greater range of currents is provided because the shorter collector plates such as 72 collect only a fraction of the number of ions which the longer plate 18 will collect for the same angular exposure. That is, if half the plate 18 is shielded and half exposed it will collect a certain amount of ions. If half of a plate such as 72 is shielded and half is exposed and the plate is only one-tenth the length of plate 18 approximately one-tenth of the number of ions will be collected on the half of plate 72 which is exposed as would be collected on one-half of the plate 18 which is exposed. Thus, if the auxiliary plate 72 is approximately one-tenth the length of the plate 18 the number of ions collected for a given angle of exposure is reduced by a factor of ten. A separate insulated lead 74 is necessary for each of the plates and the plates must be insulated from each other where it is desired to collect ion current from the plates individually.

It is apparent from the foregoing that the radiation current source provided according to the present invention is an extremely useful and simple device for supplying minute currents. The apparatus may also be considered a variable resistance since it is possible to change the current flowing without changing the potential drop in the apparatus. The accuracy and reproducibility of the current supplied by the present apparatus under constant pressure and temperature conditions has been demonstrated to be better than 1 percent.

Since many embodiments might be made of the present invention and since many changes might be made in the embodiment described, it is to be understood that the foregoing description is to be interpreted as illustrative only and not in a limiting sense.

I claim:

1. Apparatus for supplying minute currents over a wide range which comprises in combination a substantially cylindrical, gas filled, hermetically sealable chamber, a source of charged particle radiation axially disposed in said chamber, a first arcuate electrode fixedly mounted within said chamber and electrically insulated therefrom, said first electrode extending substantially the length of said chamber, a second electrically insulated arcuate electrode fixedly mounted within said chamber and diametrically opposed to said first electrode, said second electrode being substantially shorter than the length of said chamber, a third arcuate electrode rotatably mounted within said chamber and electrically connected thereto, said third electrode being rotatable between said radioactive source and said first and second electrodes, means external to said chamber for rotating said third electrode, and means for impressing a high potential between said radioactive source and said container whereby radiation emitted from said source produces ions in said chamber which are collected by said first and second electrodes and are intercepted by means of said third electrode.
2. Apparatus for supplying minute currents over a wide range which comprises in combination a substantially cylindrical, gas filled, hermetically sealable chamber, a cylindrical radioactive source holder axially disposed in said chamber, said source holder having an electrically conductive coating, a radioactive source mounted within said source holder, a first cylindrical tubular segment fixedly mounted within said chamber and electrically insulated therefrom, said first segment extending substantially the length of said chamber, a second electrically insulated cylindrical tubular segment fixedly mounted within said chamber and diametrically opposed to said first segment, said second segment being substantially shorter than the length of the chamber, a third cylindrical tubular segment mounted within said chamber electrically connected thereto and rotatable about an axis parallel to said radioactive source holder, said third segment being closer to said source holder than said other segments, means for rotating said third segment external to said chamber, and means for impressing a high potential between the electrically conductive coating on said radioactive source holder and said chamber whereby radiation emitted from said source produces ions in said chamber which are collected by said first and second segments and are intercepted by means of said third segment.
